UNITED STATES PATENT OFFICE.

LUKE SPIVEY, OF DIXON, MISSISSIPPI, ASSIGNOR OF THREE-FOURTHS
TO W. A. EDWARDS AND H. C. RUSH, OF SAME PLACE, AND JOHN
M. SPIVEY, OF EDINBURG, MISSISSIPPI.

BACK-BAND HOOK AND LINE-HOLDER.

SPECIFICATION forming part of Letters Patent No. 373,538, dated November 22, 1887.

Application filed April 23, 1887. Serial No. 235,930. (No model.)

To all whom it may concern:

Be it known that I, LUKE SPIVEY, a citizen of the United States, residing at Dixon, in the county of Neshoba and State of Mississippi, 5 have invented a new and useful Improvement in Back-Band Hooks and Line-Holders, of which the following is a specification.

My invention relates to an improved back-band hook and line-holder; and it consists in 10 a certain novel construction and arrangement of parts for service, fully set forth hereinafter, and specifically pointed out in the appended claims.

In the drawings hereto annexed, Figure 1 is 15 a perspective view of the device. Fig. 2 is a vertical central section thereof.

Referring to the drawings by letter, A designates the body of the hook, comprising a flat plate of metal having the upper and lower 20 ends curved or bent to form hooks or loops B C, respectively; and D is a transverse slot or opening in the said plate near the central point, having the rod or bar E secured therein, around which is passed the back-band F, and 25 held securely in place by the points or serrations E' or the upper edge of the said slot, adapted to engage in the said band.

G represents a hook placed in the lower loop, C, adapted to engage in a link of the trace-chain; and H is a pulley or roller having a grooved periphery journaled between the plate, 30 near the upper end, and the outer end of the loop or hook B, the function of which pulley is to guide the motion of the plow-lines while 35 driving. It will be seen that as the line is passed over the said pulley, within the hook, as shown in the drawings, it is impossible for the same to become detached, and therefore 40 there is no danger of the lines becoming entangled with the trace-chains or other parts of the harness.

The construction of the device is extremely simple, and will be found very effective. The manner of securing the back-band thereto is novel and effective, as it enables the holder to 45 be adjusted instantly to the desired height on the band. Also, the said mode of attaching the holder to the band is extremely strong, and being very simple there is no chance of the same becoming broken or damaged. 50

Having now described my invention, I claim—

1. In a back-band, the combination of the plate having the hooks B C at the upper and lower ends, hook or stud G in the lower loop, 55 and the pulley or roller H, journaled in the upper hook, substantially as and for the purpose set forth.

2. The combination of the plate having the trace holder or hook thereon, transverse slot 60 D in the said plate, the rod E therein, and the points or serrations E' in the said slot, with the back-band adapted to pass through the said slot and around the rod E therein and be engaged by the said points, substantially as and 65 for the purpose set forth.

3. The plate having the hooks B C at the upper and lower ends, the hook or stud G on the lower hook, C, the pulley or roller H, journaled in the upper hook, B, the slot D in the 70 plate, the rod E in the slot, and the points E', as set forth.

In testimony that I claim the foregoing as my own I have hereto affixed my signature in presence of two witnesses.

LUKE SPIVEY.
